The ornamental design for a handle for power shears, as shown and described.

DESCRIPTION

FIG. 1 is a perspective view of a handle for power shears showing our new design as viewed from the right side and front of the handle;

FIG. 2 is a right-side elevational view thereof;

FIG. 3 is a left-side elevational view thereof;

FIG. 4 is a top plan view thereof;

FIG. 5 is a bottom plan view thereof;

FIG. 6 is a front elevational view thereof; and,

FIG. 7 is a rear elevational view thereof.

The broken line showing of a motor assembly, strap assembly and blades is for illustrative purposes only and forms no part of the claimed design.
